RAM WITH TAPERED WEAR PLATES

Herbert Allen, Houston, Tex., assignor to Cameron
Iron Works, a corporation

Application July 2, 1937, Serial No. 151,655

4 Claims. (Cl. 251—51)

The invention relates to a blowout preventer of the type which is attached to well heads wherein a closure is to be made across the well opening.

5 It is one of the objects of the invention to provide a blowout preventer construction wherein the rams of the blowout preventer are adapted to close about a pipe in the well bore and to maintain a seal about the pipe even though the 10 pipe is subjected to rotation for long periods of time.

Another object of the invention is to provide a ram construction for blowout preventers wherein a packing and wear plates are provided in such a manner that wearing away of the packing material will be automatically compensated for by displacement of additional packing material to the wearing position by the movement of the wear plates.

20 Another object of the invention is to provide a blowout preventer ram with a tapered groove across its front face, which is arranged to receive a packing assembly in such a manner that when the assembly is forced into the groove some 25 of the packing material will be displaced and extruded forwardly to maintain a seal with the pipe in the well bore.

Another object of the invention is to provide tapered plates on a blowout preventer packing so 30 that as the wear increases the amount of packing material displaced will be increased.

Other and further objects of the invention will be readily apparent when the following description is considered in connection with the accompanying drawings, wherein:

35 Fig. 1 is a side elevation of the blowout preventer with certain of the parts shown in section and the rams in open position.

Fig. 2 is a side elevation similar to Fig. 1 but 40 illustrating the rams as being closed about a pipe in order to form a seal therewith.

Fig. 3 is a perspective view of the ram body and illustrating the grooves and recesses therein which are to receive the packing assembly.

45 Fig. 4 is a perspective view of the packing assembly.

In Fig. 1 the blowout preventer body is illustrated generally at 2 and comprises a construction which is provided with a vertical passage 3 therethrough, which is the passage from the well bore. The preventer is attached to the well head by means of the flange 4 by bolts passing through the openings 5. Any desired type of fitting for the well head may be connected to the threaded area 6 at the upper end of the blowout preventer.

Transversely of the housing 2 are the ram chambers 7 and 8 on opposite sides of the central passage 3. These chambers are arranged to movably receive the ram members 9 and 10, these ram members being identical in construction so that the description of one of them should suffice.

The chambers 7 and 8 are closed at their outer ends by a bonnet such as 12, which is held in position by the bolts 13. This bonnet carries a stem 14 which is enclosed by a stuffing box 15 and is rotatable in the bonnet, but is restrained from longitudinal movement by virtue of the retainer rings 17, one of which is positioned on each side of the flange 18 which is formed on the stem. The inner end of the stem is threaded at 20 and in this manner engaged in the cap 21 which forms a portion of the ram 10. It seems obvious that rotation of the stem 14 will cause the ram to move to and fro to open and closed position.

Particular attention is directed to the construction of the ram body 10 as best seen in Fig. 3. This body is made up of a head 25 and a shank 26. These two parts are preferably in the form of an integral casting or forging and it will be observed that the shank 26 is of less diameter than the head 25 and that a shoulder 27 defines these differences in diameter. While this ram construction is shown as circular it is to be understood that it may take any other desired configuration so long as it embodies the spirit of the invention. The forward face 29 of the ram is provided with a groove 30. This groove is somewhat tapered and extends entirely across the front face 29 of the ram, the widest portion of the groove being at the forward end. The base 31 of the groove is shown as being curved and at its end it merges with the side recesses 32, one of which is shown on each side of the head 25. These recesses 32 extend rearwardly along the side of the head to the shoulder 27.

The forward face 29 is vertically grooved with the semi-circular openings 33 which are arranged to pass about a pipe in the well bore. These openings 33 will be made of different sizes of course to accommodate different diameters of pipe. On the other hand if the preventer is to be used when there is no pipe in the well both these recesses 33 will be omitted and the face 29 will extend in a single plane across the front of the ram.

The top and bottom of the ram may be provided with a cutaway portion 34, so as to provide a flat face 35 surrounding the opening 33.

This arrangement is provided so that a coupling on the drill pipe 36 may be deposited upon the face 35 so as to support the weight of the string of pipe on the blowout preventer, if desired. In event of excessive pressures and movement of the drill pipe the collars can come in contact with this face 35 and there is a tendency to form a seat in this way for the tool joint or coupling on the pipe. A small opening 37 on the inner 10 face of each of the recesses 32 is provided in order to receive a pin which may be formed upon the inner surface of the packing member so as to assist in holding the packing assembly in position.

The shank 26 is illustrated as cylindrical but, of course, if the head 25 is of a different configuration the shank may or may not be made of this same configuration.

The packing assembly is illustrated in perspective in Fig. 4 and is made up of a packing body 40 which is of resilient material, such as rubber or other suitable substance which will flow under pressure to some extent, so that a pressure applied at one point thereof will be distributed throughout the material to provide a seal of uniform pressure at all points. This body of packing material is of a peculiar configuration in order that it may be deposited in the groove 30 and comprises a flat body portion 41 which is thickened at 42 near the rear end thereof, the beveled shoulders 43 defining the thick from the thin areas. The rear end 45 may be curved to fit the configuration of the base 31. The thin portion 41 is preferably of uniform thickness throughout its length and width and may be cut away at 47 to conform to the size and shape of the openings 33 which are to receive the pipe 36. Extending rearwardly from the body 40 are the legs 48, one of which 40 is positioned at each side at the rear of the body. These legs are of rectangular configuration except for the outer periphery 49 which may be curved to conform to the periphery of the head 25.

45 Particular attention is directed to the wear plates 50 and 51 which are positioned on the top and the bottom of the packing member in order to complete the assembly. These wear plates are deposited on each side of the thin 50 portion 41 and may be vulcanized or otherwise affixed to the rubber so that they are retained thereby and will float upon the rubber. Each 55 of these plates has a thickened forward end 53 and the plate gradually tapers away toward the rear which is the thinnest part thereof. A beveled face 54 on the inside rear of each plate is formed to cooperate with the beveled face 43 on the packing.

When the packing assembly 40 is positioned 60 in the ram it will completely fill the groove 30 and the legs 48 will be positioned in the grooves 32. As seen in Figs. 1 and 2, the packing assembly is of such size that it will project from the forward face 29 of the ram so that the front face 65 60 of the packing material and the front faces 61 of the plates 50 and 51 will all extend outwardly into the opening 3 in front of the ram. This is desirable because when the rams are moved to closed position as shown in Fig. 2 it is 70 intended that these front faces will abut against the pipe 36 in order to form a seal.

As the stem 14 is rotated the ram member will be moved forwardly and forced into engagement with the pipe. This pressure is, of course, transferred from the pipe to the ram through the face

60. It seems obvious that due to the flexibility of the packing material that this pressure will be transferred through the packing material so that it will be expanded against all of the faces of the groove 30 and transferred along the legs 48 to the grooves 32. The outer periphery of the packing will, of course, form a seal against the inside surface of the cylinder 8, so that a complete seal is formed in this manner transversely of the housing 2. 10

In event the drill stem is rotated and the friction caused by the pressure of the packing against the surface of the pipe results in wearing away of the face 60 where it contacts the pipe, then, of course, there will be a tendency for the packing material to flow forwardly to replace the material which has been worn away. In order to assist in this movement of the packing material the wear plates 50 and 51 of course are constantly applying pressure to the thickened portion 42 of the packing material. There is, of course, a tendency for the entire ram 10 to move forward and inasmuch as the wear plates 50 and 51 remain stationary, then the packing material from the thickened portion 42 will move 25 forwardly around the beveled face 54 of the wear plates and be extruded forwardly between the plates in order to compensate for wear.

The wear plates 50 and 51 being thicker at 30 their forward ends tend to be forced toward each other as the ram advances, due to the tapered faces of the groove 30. In this manner the greater the wear and the greater the movement of the ram toward the pipe, the greater 35 volume of packing material will be displaced because of the tapered construction of the groove 30 and the tapered construction of the plates 50 and 51.

In order that a seal may be formed about the head 25 of the rams an annular packing ring 70 40 is deposited against the shoulder 27 and is arranged to abut the ends 71 of the legs 48. This ring 70 is held in position by the end 72 of the cap 21, this cap in turn being clamped in position by the bolts 73 which pass through the cap 45 and are threaded into the end of the shank 26. The ram is held in non-rotatable position by the cooperating rib and groove at 74 in the bonnet 12.

It seems obvious that the cap 21 may be clamped in position with any desired pressure 50 being applied to the ring 70 so that when the packing assembly abuts against the pipe the additional pressure transmitted through the legs 48 will tend to form a peripheral seal about the rear of the head 25 so that a complete seal will 55 be formed at each side of the blowout preventer.

What is claimed is:

1. A packing assembly for valves comprising a body of resilient material, side legs thereon, the forward portion of said body being of reduced thickness, a tapered shoulder joining the thin and thick portions of the body, and a rearwardly tapering metal wear plate disposed on each side of the thinner area.

2. A packing assembly for valves comprising a body of resilient material, side legs thereon, the forward portion of said body being of reduced thickness, a tapered shoulder joining the thin and thick portions of the body, and a metal wear plate disposed on each side of the thinner area, 70 said plates being tapered with the thicker portion at the front.

3. A device adapted to abut an object to seal an opening against pressure, a packing carried by the device, means on the packing disposed

to abut and confine the packing, means to force the device toward the object to compress the packing and establish a pressure in the confined packing of a value greater than that in the opening to be closed, said first means comprising tapered plates.

4. A device adapted to abut an object to seal an opening against pressure, a packing carried by the device, means on the packing disposed to

abut and confine the packing, means to force the device toward the object to compress the packing and establish a pressure in the confined packing of a value greater than that in the opening to be closed, said first means comprising tapered plates above and below the packing. 5

HERBERT ALLEN.
